UNITED STATES PATENT OFFICE.

ALBERT L. FRANKEBERGER, OF BLOOMINGTON, ILLINOIS.

MOISTENER-TANK FOR HEATERS.

1,222,380.

Specification of Letters Patent. Patented Apr. 10, 1917.

Application filed November 11, 1916. Serial No. 130,751.

To all whom it may concern:

Be it known that I, ALBERT L. FRANKEBERGER, a citizen of the United States, residing at Bloomington, in county of McLean 5 and State of Illinois, have invented certain new and useful Improvements in Moistener-Tanks for Heaters, of which the following is a specification.

My invention relates to an improvement 10 in moistener-tanks for heaters, the present invention being particularly applicable to a type of heater used for ripening bananas, and for which I have made application for Letters Patent, filed May 22, 1916, Serial 15 No. 99,183.

The present invention is constructed and adapted, in fact of a form, to fit the chimney of that heater, it being arranged to communicate with the outlet throat of the 20 heater, through which the natural suction draws and discharges the vapor from the tank where it has been heated by intimate contact with the banana-heater chimney.

This invention consists in a tank round- 25 ed and open at the top to fit the chimney of the banana-heater, with which it is made to communicate, and provided with means at top and bottom for removably attaching it to said chimney.

30 In the accompanying drawings:—

Figure 1 is a view in perspective of the upper end of the banana-heater chimney, showing my improved moistener-tank attached;

35 Fig. 2 is a view showing the orifice or perforations in the curved elbow at the throat of the banana-heater chimney;

Fig. 3 is a view in side elevation; and

Fig. 4 is a vertical sectional view.

40 A, is the tank, it being made in any suitable dimensions, preferably more or less flat vertically, with a rounded open upper end, whereby to fit the peculiar elbow formation E at the upper end of the banana-heater 45 chimney, and, in the inner curve of the elbow E, are the perforations or orifices C, with which the open upper end of the tank

communicates with the upper end of the chimney of the heater when in place.

Wire hooks D are formed at the lower 50 inner corners of the tank to enter holes D' provided therefor in the chimney. A bail B pivoted at the top is constructed to swing over and around the elbow E to embrace the latter and cause the tank to snugly hug the 55 curvature and space formed within the elbow, as shown in the drawings.

Thus the tank is held for a considerable distance in close and intimate contact with the upper end of the chimney, so that water 60 therein becomes heated by the ascending currents of hot air, and as they pass out through the elbow E, and over the perforations C, it creates a suction of the vapor from the tank, which is discharged out into 65 the room, thus distributing itself and moistening the entire atmosphere of the room.

The tank is easily removed, but will not become accidentally displaced, owing to its construction as described. At the same time, 70 it is most effectual in performing its function to cause a distribution of moistened air from the heater.

I claim:

1. A moistener-tank open at the top and 75 provided with hooks on its inner surface for attachment to a support, and having a hinged bail which swings around said support, whereby to removably hold the tank close to its support. 80

2. The combination with a heater chimney having a curved discharge elbow at the top, with perforations or orifices on the inner curvature thereof, of a tank fitted to said curvature and having an open upper 85 end, whereby it communicates with the interior of the chimney adjacent to its discharge, and means for removably fastening and binding said tank to the chimney.

In testimony whereof I affix my signature. 90

ALBERT L. FRANKEBERGER.
